JOHNSON LOMBARD, OF SPRINGFIELD, MAINE.

Letters Patent No. 69,454, dated October 1, 1867.

IMPROVED MACHINE FOR FOLDING LEATHER.

The Schedule referred to in these Letters Patent and making part of the same.

TO ALL WHOM IT MAY CONCERN:

Be it known that I, JOHNSON LOMBARD, of Springfield, in the county of Penobscot, and State of Maine, have invented a new and improved Machine for Rolling and Folding Leather; and I do hereby declare that the following is a full, clear, and exact description thereof, which will enable others skilled in the art to make and use the same, reference being had to the accompanying drawings, forming a part of this specification, in which—

Figure 1 represents a side elevation of my improved leather-rolling machine, taken in the line xx , fig. 2.

Figure 2 is an end view of the machine.

Figure 3 is a bottom view.

Similar letters of reference indicate corresponding parts.

This invention relates to an improved machine for rolling or folding sole-leather in bundles, and consists in a set of rollers and straps in combination with a table and main rolling-shaft, by which the leather is rolled tightly for packing and transportation, as hereinafter more particularly described.

A strong rectangular horizontal frame, A, is mounted on small casters $a a$ at the four corners, for conveniently moving from place to place on the floor of a loft or storehouse. On one end of the frame A is hinged at $b b$ a large table, B, for receiving the sides of leather to be rolled, and which is placed horizontally for that purpose, but may be folded up out of the way when not in use. Two strong uprights, C C, are fixed centrally in opposite sides of the frame A. On the tops of the posts C C are hinged two pieces, D D, framed together by a cross-bar, D', for bearings to support the rollers $e e^1$. The bearings D D are turned forward on the hinges $d d$, to hang over the table B, when the leather is to be rolled, as shown in red lines, fig. 1, and rise when the operation of rolling is performed, to the position shown in fig. 1. A double standard or upright frame, E, is fixed upon the rear end of the frame A, opposite the table B, to serve as bearings for rollers $e^2 e^3$. The main leather-rolling shaft or roller F is hung in the posts C C, in bearings that may be closed or opened by sliding front pieces $e e$, to secure the roller in place when in operation, or let it be thrown out with the leather wound upon it after the operation. In the middle of the table B a roller, e^1 , is hung upon a slide, g, in an opening or slot in the table, for the purpose of moving forward or back, as required. The slide g is operated by a roller, e^1 , moved by a crank, h, at the side of the table. The slide g is connected with the roller e^1 by a strap, k, and a lever-brake, m, is hung under the table, near the roller e^1 , with which it is connected by a strap, m', to hold it fast in a rack, m'', and thus control the slide g as required. A main broad leather band or belt, n, passes under the main shaft F, over and under the rollers $e e^1$, over and under the rollers $e^2 e^3$, and around the pulley e^4 , as shown in fig. 1, for the purpose of bearing upon the leather when wound upon the shaft, and keeping the bundle close and compact in shape until it is tied up. Two straps, p p, are fastened at one end of each to the table B, on the side next the roller F, and passing under and behind the roller F, are also fastened at the other end of each to the roller e^1 , for the purpose of bearing against the bundle of leather after it has been rolled up and tied on the roller F, and throwing the handle and roller together forward on the table B, by turning the roller e^1 with the crank h^2 , fig. 2. On one end of the main shaft F is a spur-wheel, s, which gears into a pinion, t, operated by a crank, h^2, when in place in its bearings, ready for turning and rolling or winding a side of leather on the shaft. In the side of the main shaft F is made a longitudinal recess, f, for receiving the end of a side of leather when it is laid on the table B, to be rolled up around the shaft, as shown in red lines in fig. 1.

Having thus described my invention, what I claim as new, and desire to secure by Letters Patent, is—

1. The table B, hinged to the horizontal frame A, as and for the purpose described.

2. The combination of rollers $e e^1$, hung in the hinged side pieces D D, the rollers $e^2 e^3$, hung in the double standard E, the roller e^1 , hung in the slide g, on the table B, the main shaft F, hung in the posts C C, and the belt n, passing over all the rollers, the whole being arranged and operating substantially as and for the purpose herein described.

3. The slide g and the brake m, in combination with the roller e^1 , arranged and operating as described.

The above specification of my invention signed by me this 24th day of June, 1867.

JOHNSON LOMBARD.
